United States Patent Office

Des. 198,695
Patented July 21, 1964

198,695

SKI POLE GRIP

William Cameron, 3969 Cowan Road, Lafayette, Calif.,
and Laurence G. Powers, 715 B St., Hayward, Calif.

Filed Dec. 16, 1963, Ser. No. 77,818

Term of patent 14 years

(Cl. D34—14)

FIG. 1

FIG. 2

FIG. 3

FIG. 4

FIG. 1 is a side elevational view of a ski pole grip, showing our new design;

FIG. 2 is a front elevational view thereof;

FIG. 3 is a rear elevational view; and

FIG. 4 is a cross sectional view of the grip taken along the plane indicated at 4—4 in FIG. 1.

We claim:

The ornamental design for a ski pole grip, substantially as shown.
